US0D1074511S

(12) **United States Design Patent** (10) **Patent No.:** **US D1,074,511 S**
(45) **Date of Patent:** **** May 13, 2025**

(54) **ANTI-WEAR SHEET**

(71) Applicant: **Liang Zhang**, Yongzhou (CN)

(72) Inventor: **Liang Zhang**, Yongzhou (CN)

(**) Term: **15 Years**

(21) Appl. No.: **29/902,943**

(22) Filed: **Sep. 19, 2023**

(30) **Foreign Application Priority Data**

Apr. 10, 2023 (CN) 202330188236.2

(51) **LOC (15) Cl.** **03-01**

(52) **U.S. Cl.**

USPC **D3/318**

(58) **Field of Classification Search**

USPC D11/201, 754; D2/605, 609, 754;
D3/222, 226, 228, 249, 318, 324;
D8/356
